UNITED STATES PATENT OFFICE.

JOHN C. KENNEDY, OF BOSTON, AND WILLIAM S. KINSLEY, OF READING,
MASSACHUSETTS.

GUMMED-STRIP APPLIER.

1,026,446.

Specification of Letters Patent.

Patented May 14, 1912.

Application filed May 21, 1910. Serial No. 562,735.

To all whom it may concern:

Be it known that we, JOHN C. KENNEDY, of Boston, in the county of Suffolk, and WILLIAM S. KINSLEY, of Reading, in the county of Middlesex, both in the State of Massachusetts, have invented certain new and useful Improvements in Gummmed-Strip Appliers, of which the following is a specification.

10 This invention relates to devices for applying gummmed strips to packages, and especially to that type of such devices which provide for feeding a strip of paper which is gummmed on one side, in order that said strip may be employed in the place of wrapping strings or cords or sealing wax, for securing wrapped parcels or for temporarily securing together two or more assembled parts which are not covered by a 20 wrapper.

The particular object of the present invention is to provide a device of this character which will never leave any moistened portion of the strip in the implement, so as 25 to preserve the unapplied end of the strip always in condition for the next use.

Another object is to provide a structure having a combined lock and brake for a strip reel, to prevent any accidental excessive 30 unwinding of the strip.

Another object of the invention is to provide an improved hand implement of this character which can be readily grasped for hand manipulation, and having a strip feed 35 which can be easily controlled by the user.

Other objects of the invention are to provide a simple implement of this type having improved details of construction which will be more fully pointed out hereinafter.

40 To these ends the invention consists in the construction and combination of parts substantially as hereinafter described and claimed.

Of the accompanying drawings,—Figure 45 1 represents a longitudinal section of the device in its preferred form. Fig. 2 is a plan view of the same, parts being broken out to facilitate illustration. Fig. 3 represents a section on line 3—3 of Fig. 1. Fig. 4 represents a section on line 4—4 of Fig. 1. Fig. 5 represents a section on line 5—5 of Fig. 1. Fig. 6 is a perspective view representing the device in use. Fig. 7 is a side elevation, partly in longitudinal section of another

embodiment of the invention. Fig. 8 is a 55 view similar to Fig. 7, but with the reservoir and wick tube and some of the other parts removed or broken out. Fig. 9 represents an under plan view of a portion of the structure illustrated in Fig. 7. Fig. 10 60 represents a section on line 10—10 of Fig. 8. Fig. 11 represents a section on line 11—11 of Fig. 8. Fig. 12 represents a partial edge view showing a detail hereinafter described.

Similar reference characters indicate the 65 same or similar parts in all of the views.

Referring first to the structure illustrated in Figs. 1 to 6 inclusive, the body or casing of the device, and which forms a reservoir for water is shown at 15, a wick tube or 70 throat 16 leading from one end of the reservoir portion of the casing, a wick 17 of felt or other suitable material occupying said tube or throat and extending into the reservoir portion which latter has a suitable 75 opening for filling it, said opening being closed by a stopper 18. Side walls or flanges 19 rise from the casing 15 and have inwardly formed lips 20 at their edges which lips serve to limit the upward movement or 80 position of a movable cutter and a strip feeding member hereinafter described. Near one end of the casing and above the wick throat or tube is a plate 21 which is suitably fixed in position, as by screws 22, the 85 front edge of said plate being sharpened, and preferably inclined laterally as shown at 23 in Fig. 3 so as to form a shearing edge to coöperate with the upper cutter bar presently described, to sever the gummmed strip. 90 The movable cutter and strip-feed member comprises a lower plate 24 and an upper plate 25, the latter having an opening 26, the two plates having a passage way between them for the gummmed strip *a*. This 95 cutter and feed member is pivotally mounted at its rear end as by means of cone-tipped screws 27 (see Figs. 2 and 4) and between said cutter and feed member, and the top of the wick tube or throat, is a spring 28, the 100 object of which is to hold the lower plate 24 up against the lips 20 with sufficient pressure so that the thumb or finger of one hand of the user may be used to press upon the portion of the strip *a* exposed at the opening 105 26 and slide the strip along toward the exit or tip of the device, the spring, however, having sufficient strength so that it will not

yield when feeding the strip, but can yield under a greater pressure imparted for the purpose of severing the strip. To prevent movement of the strip *a* in the wrong direction, and to prevent it from being pulled backward, a suitable toothed detent plate 29 is secured to the upper wall of the reservoir casing, the toothed edge projecting through an opening in the plate 24 to engage the under surfaces of the strip. The front end of the plate 25 carries a cutter bar 30, said bar being suitably attached to said plate as by means of a plate 31 of the bar 30, lying on top of the plate 25, and secured thereto by screws 32. Substantially in line with the cutter bar 30, and extending to the front end or tip of the device, is a cover 33 which is provided with a notch 34, and is mounted in slideways of the side walls 19, so as to enable the cover to be slid out when it is desired to gain access to the exposed end of the wick. Said slide 33 constitutes the upper wall of the exit aperture for the strip, the lower wall of which is formed by an inclined surface 35 of the body of the implement, the said inclined bottom 35, and the under surface of the cover 33, constituting a tapering throat to guide the end of the strip after it is fed beyond the cutters, so that the end of the strip will be guided up to the top of the moistening wick.

The device is especially a hand implement and so designed for use in a manner that it will either apply short sections to overlapping edges of a wrapping paper, or to any surface to which the gummed strip is secured, this being hereinafter referred to as the strip-supporting surface, or, if desired, so that a longer section of the strip can be carried entirely around a package or bundle. In order that the device, after being laid aside, may be readily grasped for use again, we prefer to attach to the device a foot or support 36, the end of said support being indicated as attached by screws 37 to the under side of the casing 15.

The use of the device is indicated in Fig. 6, although said figure does not illustrate the foot or support 36, this latter not being an essential feature, although a desirable one. The user grasps the implement and with a thumb or finger engaging the strip through the opening 26, pushes the strip *a* out, and in doing so, the gummed surface which, of course will be the under side, is passed over the end of the wick and thereby moistened. The projecting moistened end is pressed upon the strip-supporting surface by a finger or thumb of the other hand of the user, and then by drawing the implement backward as great a length of the strip will be pulled out as may be desired the gummed strip being moistened as it is drawn. When the desired length has been pulled out, a greater pressure is exerted on

the cutter and strip-feed member, so as to overcome the force of the spring 28, and cause the bar 30 to coöperate with the edge 23 to sever the strip with a shearing cut. The point at which the cut is made is at the rear of the moistener and the implement will then be drawn backward to pull out the remaining end of the portion of the strip which will then be pressed down upon the strip-supporting surface by the user. It will therefore be seen that no portion of the gummed strip can possibly be left in contact with the moistening wick because the implement can not be separated from the strip-supporting surface without pulling out the portion of the strip which was in the tip of the implement when the cutter was operated. During the operation of drawing out the strip, the tip 38 may be employed to bear down upon the strip so as to press it firmly on the strip-supporting surface during the act of moving the implement along.

One of the side walls 19 is formed with an extension or wide wing carrying a rigidly secured stud 40 to constitute a bearing for a strip reel. The stud has a transverse recess 41 in which is mounted a bolt 42, carried by a spindle 43 passing through the bottom of the recess and having an upset end 44 to keep the spindle and bolt in place. A spring 45 between the bolt and the bottom of the recess projects the bolt with a yielding pressure against the bottom of an internal annular groove 46 formed in the sleeve or reel 47.

The sleeve or reel, having the gummed strip wound thereon, may be simply slipped onto the stud 40 until the annular groove 46 catches over the bolt so that the reel is locked in place. At the same time, the head of the bolt, by its friction against the bottom of the annular groove, constitutes a brake to prevent the strip from becoming loose or being run too far through the device.

Referring to Figs. 7-11 inclusive, a reservoir body or casing 15, having a wick throat or tube 16, a wick 17, and a stopper 18 are similar to the parts already described and having the same numerals in the preferred form. These parts are mounted in an inclosing frame comprising side walls 50, a bottom cross piece 51, and a rear cross piece 52. Secured to said frame is an upper handle 53, a lower and movable handle 54 being formed as a lever 55 having its front portion divided so as to constitute a yoke shank pivoted in the frame at 56, the members of the yoke carrying a bridge piece 57 having fingers 58 (Figs. 8 and 10). The frame carries a fixed guiding strip 59 to the front end of which is secured an upper cutter bar 60, in advance of which is mounted a slide cover 61, similar to the cover 33 in Fig. 1. A plate 62 upon the reservoir and wick

throat has its front end turned up and the edge sharpened to form a lower cutter member 63 to coöperate with the cutter bar 60 to sever the strip *a* which is fed through the 5 guide 59 in the manner hereinafter described. The plate 62 is pivoted at 64 and is held normally depressed or in the position shown in Fig. 7 by a spring 65. The under wall of the strip guide 59 is formed with 10 an opening or longitudinal slots 66 to permit of the operation of the feeding teeth hereinafter described. Mounted on guide ribs 87 (see Fig. 8) are two rack slides 67 (see Figs. 7 and 8), the teeth of which are engaged by pinions 68 mounted in a shaft 69 having a ratchet wheel 70. Said ratchet wheel is engaged by a pawl 71 which is pivoted at 72 to the front end of a lever 73 which latter is pivoted in the frame at 74 and is normally held in the position shown 20 in Fig. 8 by a spring 75. Said pawl has a heel 76 between which and the bottom of a socket in the lever 73 is a coil spring 77, the tendency of which is to preserve an 25 operative engagement of the pawl and ratchet to actuate the latter in one direction but to permit the pawl to move in the other direction without rotating the shaft 69 and its pinions 68. The lever 73 is provided 30 with a stud 78 in position to be engaged by one of the yoke members 55. A stop lug 79 projects inwardly from one side of the frame to limit downward movement of the lever 73 and its pawl. A spring 80 is connected at one end to a cross bar 81 which 35 connects the two slide racks 67, the other end of the spring being connected to a fixed pin 82. A rock shaft 83 is mounted in the front end of the slide racks and has teeth 84 which pass upwardly through the opening or slots 66 so as to engage the under surface of the gummed strip. The said rock shaft is provided with a rearwardly extending lug 85 upon which a spring 86 bears to 40 normally hold the teeth 84 in position to properly engage the gummed strip, but to permit the rock shaft to yield sufficiently so that the teeth 84 will not tear or mutilate the strip during the backward movement of 45 said teeth. Fixed to one side of the upper fixed handle 53 (see Figs. 7, 8 and 11) is a strip 88 having a shoulder 89 which normally stands in the path of one upper corner of the lower movable handle or lever 54, 50 said shoulder or detent being at such height as to serve as a stop to prevent the lever 54 from being raised to its full extent, but which stop may be pushed aside by one finger of the user so as to let the lever 54 pass by the shoulder 89 to complete its 55 movement.

In the use of the implement shown in Figs. 7-11, the user grasps the two handles and operates them in a manner similar to 60 shears. The lever 54 may be actuated as

many times as desired, being stopped each time by the detent shoulder 89, until such of the strip has been fed out as may be wanted, this operation being due to the fact that the yoke bar 55 engages the stud 78, 70 lifts the lever 73, and causes the pawl 71 to rotate the shaft 69 so that the pinions 68 cause the slide racks to advance or move in a direction so that the teeth 84 will push the strip out over the end of the wick. A 75 succession of such movements will advance the strip step by step without doing any cutting because the lever 54 has not moved far enough to actuate the cutter. Of course, however a single actuation of the lever 54 80 may be used to advance enough of the strip so that its outer end can be pressed down on the strip-supporting surface in the manner similar to that illustrated in Fig. 6, after which the implement may be drawn 85 backward so as to pull out more of the strip. Whenever a sufficient length of the strip has been fed out or pulled out, the user simply pulls the detent strip 88 aside so that the lever 54 can pass the shoulder 89. 90 Upon then moving the lever 54 as far as it can go, the fingers 58 will then engage and lift the plate 62 so that the cutting edge 63 thereon will coöperate with the cutting edge of bar 60 in cutting or shearing the strip. 95 In order that this last mentioned movement of the lever to perform the cutting operation will not still further advance the feeding mechanism, the pawl 71 is provided with an untoothed portion 90 (see Fig. 8) which untoothed portion arrives opposite the teeth of ratchet wheel 70 every time that the lever 54 contacts with the detent shoulder 89. It will therefore be seen that the operation of the lever 54, until stopped by the shoulder 100 105 89 will rotate the shaft 69 and advance the strip in the manner described, the fingers 58 being then only just in contact with, or about to engage the under surface of the edge portions of the plate 62 which carries 110 the lower cutter; and it will be seen that when the detent shoulder 89 is displaced, and the lever 54 given further upward movement, the untoothed portion 90 of the pawl 71 will prevent any further feeding of the 115 strip, while the fingers 58 will actuate the cutter to sever the strip.

Of course the reel support structure shown in Figs. 1, 2 and 3 may be applied to the form shown in Figs. 7 and 8.

In each form illustrated, we have provided a guide for a gummed strip, a moistener consisting of the end of the wick adjacent the exit for the strip, and cutters which sever the strip at a point in the rear of the moistener. Therefore there can by no possibility be a piece of gummed paper left in contact with the moistener so that the gum of the strip could be taken up by the wick, and cause such an accumulation 130

of the gum as would interfere with the usefulness of the wick. If this does happen, however, the slide plate or cover over the exit throat for the strip can be removed and a small portion of the wick trimmed off, and the rest of the wick then pulled forward to the former degree. If the gummed strip could remain in contact with the moistener when the device is laid aside, the gum 10 would be so soaked off that the front end of the strip would not adhere when next used. And it will be seen that in each form there is an exit throat for the strip leading from the cutter to the moistener, and that 15 the applying tip is at the end of the strip guide, the moistener being closely adjacent thereto, the cutter being in the rear of the moistener. This structure facilitates the use of the implement in the manner illustrated in Fig. 6, and it is of course to be understood that the implement shown in Figs. 7-11 inclusive can be used in the same manner as indicated in Fig. 6, but the feed of the strip and the cutting of it being 20 performed by a movement of the fingers of the hand similar to the use of shears, instead of by the direct operation of one finger or thumb of the user.

The implement may be provided with a 30 flap 95, Fig. 12, adapted to bear upon the upper side of the projecting end of the strip *a* and receive the pressure of the operator's thumb or finger. Said flap is flexibly connected with a suitable part of the implement, such as the cover 33 and may be a strip of sheet rubber.

The device is, of course, capable of being used for other purposes than that of supplying a gummed strip for securing parcels, and it is to be understood that we do not limit ourselves to such use. It is obvious that the strip might be a printed or lithographed one, which, when cut up, will supply labels. Since the operator can readily control the point of severance, and since either the end of tip 38 or one end of the opening 26 can be used as a gage, in connection with any markings of the labels, to enable the operator to determine how far the strip should be drawn or fed out, the proper point for operating the cutter may be readily determined, so that such a strip of labels may be accurately cut. It is also obvious that after a section has been cut off and applied, the tip 38 can be run back and forth as a presser so as to firmly affix such section. And instead of employing a previously gummed strip *a*, an un-coated strip may be used, and in such case the reservoir 15 will 50 be supplied with any suitable paste or adhesive. The throat 16, owing to its leading from the reservoir to a point between the tip 38 and the cutter, constitutes means for rendering the strip adhesive either by supplying water to a previously gummed strip so

as to impart to the dry gum an adhesive quality or by supplying both the gum and the moisture in the form of paste. In either case, there is a certainty that no portion of the strip will remain in the implement in 70 sticky condition, owing to the location of the end of the throat 16, as described, between the cutter and the tip 38.

We claim:

1. A hand implement of the character described, comprising a guide for a gummed strip, a moistener adjacent the exit for the strip, and a movable manually operable cutter for severing the strip at a point in the rear of the moistener, the implement having 75 a form to enable it to be manipulated by one hand of the operator to apply and cut off a strip of any length.

2. A device of the character described, comprising a guide for a gummed strip, an 80 applying tip at one end of the guide, a moistener adjacent said tip, and a strip cutter in the rear of the moistener.

3. A device of the character described, comprising a guide for a gummed strip, a 85 tapering exit throat for the strip, a moistener adjacent the tip of the device, and a cutter for severing the strip at a point in the rear of the moistener, said tapering exit 90 throat leading from the cutter to the moistener.

4. A device of the character described, comprising a strip guide having an elongated opening to permit a gummed strip to be engaged by a thumb or finger for feeding 100 it, a moistener adjacent the exit for the strip, and means for severing the strip at a point in the rear of the moistener.

5. A device of the character described, comprising a guide for a gummed strip, a 105 reservoir, a wick throat leading from said reservoir, a movable cover plate opposite the end of said wick throat, and means for severing the strip at a point in the rear of the end of the wick throat.

6. A device of the character described, comprising a guide for a gummed strip, a reservoir, a wick throat leading from said reservoir, a movable cover plate opposite the end of said wick throat, and means for severing the strip at a point in the rear of the end of the wick throat, the passage way for the strip between the cutter and the end of the wick throat being tapering.

7. A device of the character described, comprising a reservoir, a wick throat leading therefrom, a strip guide, a cutter, and a fixed support or foot piece for holding the implement in position to facilitate its being grasped, said support consisting of a bow-shaped flat strip of metal having its ends fixedly secured to the reservoir near the front and rear ends thereof.

8. A device of the character described, comprising a body having a moistener, a

strip guide pivoted at one end and having a cutter at the other end, and means carried by said body to coöperate with the said cutter for severing the strip, said body having 5 an exit aperture for the strip in alinement with the strip guide when the latter is in normal position.

9. A device of the character described, comprising a body having a moistener, a 10 strip guide pivoted at one end and having a cutter at the other end, and means carried by said body to coöperate with said cutter for severing the strip, and a spring interposed between the body and the strip guide 15 to hold it normally in position for feeding, said body having an exit aperture for the strip in alinement with the strip guide when the latter is in normal position.

10. A device of the character described, 20 comprising a body having a moistener, a strip guide pivoted at one end and having a cutter at the other end, means carried by said body to coöperate with said cutter for severing the strip, a spring interposed between the body and the strip guide to hold 25 it normally in position for feeding, the strip guide having an elongated opening to permit the strip to be engaged by the thumb or finger of the user, and a detent to prevent 30 backward movement of the strip.

11. A device of the character described, comprising a frame or casing having an extension provided with a stud, a reel mounted on said stud, said stud having means to co- 35 operate with such reel to hold it on the stud and retard rotary motion of the reel, and a moistener and cutter carried by said frame or casing.

12. A device of the character described, 40 comprising a frame or casing having an extension provided with a stud to support a reel, said stud having a transverse recess, a spring projected bolt in said recess, a moistener and cutter carried by the frame or cas- 45 ing, and a reel adapted to be mounted on

said stud and having a portion to coöperate with said bolt for the purpose described.

13. A device of the character described, comprising a guide for a gummed strip, a moistener adjacent the exit for the strip, 50 means for severing the strip at a point in the rear of the moistener, and a flap flexibly connected to the device and adapted to bear on the projecting end of the gummed strip.

14. A hand implement of the character 55 described, comprising a guide for a strip, means adjacent the exit for the strip for rendering said strip adhesive, and a manually controlled cutter for severing the strip at a point in the rear of the means for rendering the strip adhesive, the implement having a form to enable it to be manipulated by one hand of the operator to apply and cut off any length of section of the strip.

15. A hand implement of the character 65 described, comprising a guide for a strip, a presser at one end of the implement, a strip cutter, and means located between the cutter and presser for rendering the strip adhesive.

16. In a device of the character described, 70 the combination with a tank adapted to serve as a handle for operating the device, of damping means carried by said tank and supplied therefrom for making the strip adhesive, a presser arranged in advance of 75 the said damping means, means rearwardly of said damping means whereby the strip may be fed an indeterminate quantity of movement, and means for severing a section of strip from a continuous roll, arranged between said damping means and said feeding means.

In testimony whereof we have affixed our signatures, in presence of two witnesses.

JOHN C. KENNEDY.
WILLIAM S. KINSLEY.
